UNITED STATES PATENT OFFICE.

MANSEL E. NAYLOR, OF LOS ANGELES, CALIFORNIA.

LOCK.

Application filed May 4, 1920. Serial No. 378,766.

To all whom it may concern:

Be it known that I, MANSEL E. NAYLOR, a citizen of the United States, residing at Los Angeles, in the county of Los Angeles 5 and State of California, have invented certain new and useful Improvements in Locks, of which the following is a specification.

This invention relates to improvements in locks and has for its object to provide a 10 sliding door lock, catch and handle.

Another object of the invention is to provide a sliding door lock especially adapted for garages, barns, warehouses, freight cars, etc., etc., in which a hasp member is provided for overlapping edges of doors or door 15 and frame.

With the above and such other objects in view as will hereinafter more fully appear, I have invented the device illustrated in the 20 accompanying drawings in which—

Figure 1 is a transverse section of a pair of doors, partly broken away and embracing my invention,

Figure 2 is an enlarged elevational view 25 thereof,

Figure 3 is a similar view showing the latch member thrown open,

Figure 4 is a section on line 4—4, Figure 2, and

Figure 5 is a view similar to Figure 1, showing a slight modification.

Like reference characters indicate like parts throughout the following specification and in the several views in the drawings in which 1 is a sliding door and 2 either a sliding door or a door frame. These members are locked together by means of my combined lock latch and handle device 3, which combination includes a hinge member 4 having stuck out wings 5 and 6 which form a bearing for the pintle 7 upon which the hinge end 8 of the hasp 9 is rolled to complete the hinge. The hasp 9 is bent at right angles at 10 to an extent equaling the thickness of the end 11 of the door 1 and terminates in a parallel offset 12 having a bore 13 through which the reduced threaded end 14 of the crank handle 15 is projected. Screwed on eccentrically to said end 14 is 40 a latch member 16 which is adapted to project into the similarly shaped opening 17 of the latch plate 18 which is bolted to the sliding door, or fixed casing as the case may be, 2. A recess 19 is provided in the member 2 aligning with the opening 17, to receive the latch 16. The lower end 20 of

the handle 15 projects below the lower end 21 of plate and a staple 22 is hinged to the lower edge of said plate and is adapted to be swung over said handle 15, after which 60 a padlock 23 is secured through the opening 24 in said lower end 20 of said handle, thus preventing the disconnection of the staple 22 with said handle, whereby the doors or door and casing are securely 65 locked together. Certain bolts 25 of member 4 come under the hasp 9 when closed and the outer end 12 of the hasp covers the bolts 26 of plate 18 whereby said members can not be unbolted when locked.

In Figure 5 I show a slight modification in which the hasp 26 is straight so as to be used on doors the edges of which abut.

My invention is set forth in the following claims:—

1. A door fastener embracing a hinged plate and a fixed plate having an opening, a crank handle carried by and rotatably mounted in the end of the first plate and having a latch to project through the opening in said second plate and engage the inner surface thereof, a loop hinged to the lower end of said second plate and adapted to swing up over said handle. 80

2. A door fastener embracing a hinged plate and a fixed plate having an opening, a crank handle carried by and rotatably mounted in the end of the first plate and having a latch to project through the opening in said second plate and engage the inner surface thereof, a loop hinged to the lower end of said second plate and adapted to swing up over said handle, said handle having an opening for engagement with a padlock. 85

3. A door fastener embracing a hinged plate and a fixed plate having an opening, a crank handle carried by and rotatably mounted in the end of the first plate and having a latch to project through the opening in said second plate and engage the inner surface thereof, a loop hinged to the lower end of said second plate and adapted to swing up over said handle and means for preventing the release of said loop from 95 said handle. 100

4. A door fastener embracing a hinged plate and a fixed plate having an opening, a crank handle carried by and rotatably mounted in the end of the first plate and having a latch to project through the opening in said second plate and engage the 110

inner surface thereof, a loop hinged to the lower end of said second plate and adapted to swing up over said handle and means for preventing the release of said loop from said handle, said means consisting of a padlock engageable with the end of said handle.

5. A door fastener embracing a crank handle and a latch and a lock securable to said handle whereby the latch is held in 10 operative position, a loop adapted to swing over said handle, said lock being adapted to hold the loop in engagement with the handle.

6. A door fastener consisting of a sheet 15 metal clasp having a flat end, provided with an opening and a crank latch handle carried thereby and rotatably mounted in the opening, a fixed plate having an opening through which the latch projects, a U-shaped 20 loop both ends of which are pivoted to the fixed plate and adapted to be swung over said handle to hold the same against movement.

7. A door fastener and handle including a 25 hinged plate having a rotatable crank handle carried thereby and a latch on the handle adapted to hold it against movement through said plate, a fixed plate having an opening into which latch projects and 30 fastens, said last plate having a depending extension and means thereon for engagement with the handle.

8. A door fastener and handle including a hinged plate having a rotatable crank 35 handle carried thereby and a latch on the handle adapted to hold it against movement through said plate, a fixed plate having an opening into which latch projects and fastens, said last plate having a depending extension and means thereon for engagement 40 with the handle, said means consisting of a pivoted loop.

9. A door fastener and handle including a hinged plate having a rotatable crank handle 45 carried thereby and a latch on the handle adapted to hold it against movement through said plate, a fixed plate having an opening into which latch projects and fastens, said last plate having a depending extension and means thereon for engagement 50 with the handle, said means consisting of a pivoted loop adapted to swing up over the handle when in latching position.

10. A door fastener and handle including a hinged plate having a rotatable crank 55 handle carried thereby and a latch on the handle adapted to hold it against movement through said plate, a fixed plate having an opening into which latch projects and fastens, said last plate having a depending extension and means thereon for engagement 60 with the handle, said means consisting of a pivoted loop adapted to swing up over the handle when in latching position and means for holding said loop in 65 engagement with the handle.

11. A door fastener and handle including a hinged plate having a rotatable crank handle carried thereby and a latch on the handle adapted to hold it against movement 70 through said plate, a fixed plate having an opening into which latch projects and fastens, said last plate having a depending extension and means thereon for engagement 75 with the handle, said means consisting of a pivoted loop adapted to swing up over the handle when in latching position and means for holding said loop in engagement with the handle, said last means consisting of a padlock secured to said handle. 80

12. A door fastener consisting of a sheet metal clasp having a flat end, provided with an opening and a crank latch handle carried thereby and rotatably mounted in the opening, a fixed plate having an opening through 85 which the latch projects, a U-shaped loop both ends of which are pivoted to the fixed plate and adapted to be swung over said handle to hold the same against movement, said handle having an opening to secure a 90 padlock thereto, whereby said loop is held in engagement with the handle.

13. A door fastener embracing a crank handle and a latch and a lock securable to said handle whereby the latch is held in 95 operative position, a loop adapted to swing over said handle, said lock being adapted to hold the loop in engagement with the handle, and a fixed plate with which the latch is engageable, said loop being hinged to said 100 plate.

In testimony whereof I affix my signature.

MANSEL E. NAYLOR.
